United States Patent Office.

OTIS W. STANFORD AND SELDEN S. SCOVILLE, OF LEBANON, OHIO.

Letters Patent No. 77,413, dated April 28, 1868.

IMPROVED WASHING-MACHINE.

The Schedule referred to in these Letters Patent and making part of the same.

TO WHOM IT MAY CONCERN:

Be it known that we, OTIS W. STANFORD and SELDEN S. SCOVILLE, both of Lebanon, Warren county, Ohio, have invented a new and useful Washing-Apparatus; and we hereby declare the following to be a full, clear, and exact description thereof, reference being had to the accompanying drawings, making part of this specification.

The first part of our invention relates to devices for rubbing the clothes, which consist in part of two battens, that are operated in such a manner as to alternately press and then rub the garments.

The second part of our invention consists in a frame supported on springs so as to yield in every direction, and provided with a series of rollers, which, in conjunction with the battens, serve to wash the garments in the most thorough and expeditious manner, and without any liability of injuring the most delicate fabrics.

The third part of our invention consists in dividing the tub of the washing-apparatus into a number of compartments or chambers, in which the washing, rinsing, and starching operations may be consecutively performed, and combining therewith battens capable of being operated in either of these chambers, by being connected to a shiftable lid, which may be slid along and secured at any desired part of the tub, as may be found most convenient.

The fourth part of our invention consists in a movable holder for the support of a "wringer," the holder being contrived so that the wringer can be operated above either of the compartments of the tub.

The remaining portions of our invention relate to subordinate devices, which will be explained in the sequel. In the accompanying drawings—

Figure 1 is a perspective view of a "washing-apparatus" embodying our improvements, the shiftable lid being represented as somewhat elevated.

Figures 2 and 3 are, respectively, longitudinal and transverse sections of the same; and

Figure 4 is a perspective view of a portion of the rear side of the tub, showing the devices by which the shiftable lid is permitted to be moved along the tub, and maintained at any desired position.

The tub of our washing-apparatus consists of a long rectangular box, A, supported upon legs a a', and it is provided with vertical partitions, B B' B'', which divide said tub into four chambers or compartments, C, D, E, and F, the first two being used for the washing operations proper, and the last two, respectively, for the rinsing and starching of the clothes.

The two washing-chambers, C and D, are provided with frames, g h, in which is journalled a series of rollers, G H, and said frames are adapted to yield in every direction by being supported upon springs I, which rest upon the bottom of the tub, so as to form a yielding bed of rollers.

A number of these rollers may be somewhat diminished in diameter near their mid-length, as shown at G' H', so as to permit of the suds passing more freely through the bed at those parts.

The battens consist of frames J J', which are composed of wooden slats, and these battens are rigidly attached to their stems, j j', whose upper ends are pivoted to the arms k k' of a rock-shaft, K.

The lower ends of the stems j j' are united by a link, L, which prevents the battens coming in contact with one another at any portion of their stroke, and is also coeffective for the production of a rubbing-motion, as will hereafter appear.

The rock-shaft K is journalled in standards M M', which rise vertically from the shiftable lid N, and said rock-shaft is provided with a socket, o, for the reception of a lever or handle, O, by which the shaft and the accompanying battens are operated.

The shiftable lid or cover N has slots, n n', within which the stems j j' vibrate, and this lid is hinged at p p' to a carriage, P, which is adapted to slide upon a guide-bar, Q, the latter being secured to the rear side of the tub.

This provision of the hinged lid N, carriage P, and guide-bar Q, permits of the battens being employed in either of the chambers C, D, or E, as may be desired.

Hinged to the lid N is a weighted catch, R, having a rearwardly-projecting stud, r, which, entering either of the apertures s in the tub A, prevents accidental elevation of the lid.

Secured to the under side of the lid N are battens S, which serve to stiffen the lid, and also to prevent the escape of steam and water when the tub is quite full.

Attached to the front side of the tub is another guide-bar, T, which supports a movable wringer-holder, U, the latter being secured at any position upon said guide-bar by means of the set-screw u.

The carriage P, to which the lid is hinged, is provided with a spring-bar, V, which being permitted to engage with notches, v, at such points as to permit of the battens being used in either of the chambers C, D, or E, as may be necessary.

W is a waste-pipe, and communication is made between said pipe and the different chambers by means of cocks c d e f, by which arrangement either of the chambers can be emptied of the suds without disturbing the contents of the neighboring compartments.

X is a furnace for heating the water in the washing-chambers.

The operation of our washing-machine is as follows: The washing-chambers being filled with a sufficient quantity of hot water or suds, and the clothes laid upon the bed of rollers, the lid is closed and secured by engaging the stud r of the weighted catch in the aperture s.

The operator then grasps the handle O, and by moving it alternately backward and forward, the battens are made to operate upon the clothes contained in the tub.

The action of the battens will be understood by referring to fig. 3, and it will be seen that the one, J, which is supposed to be descending, first squeezes the clothes between it and a portion of the rollers, and as the frame which carries these rollers is supported on springs, it yields sufficiently to prevent the clothes being injured by too great a compression.

One end of the frame being thus depressed, the suds below it are forced up through the rollers at the other end, carrying the clothes along with them, and forcing the water through the interstices of the fabric.

As some of the rollers are decreased in diameter near their mid-length, the suds are allowed to pass freely through the bed at those parts.

The method in which the rock-shaft, stems, and link are arranged, causes the battens to have a sliding motion above the rollers, when near the end of the stroke, by which means the clothes are not only compressed, but they are also rubbed and washed in the most thorough manner. As each of the battens is elevated or depressed, it operates on the clothes in the manner described; and with such effect that the clothes are washed in a few minutes.

The clothes having been washed, are then placed in the rinsing-chamber E, and the sliding lid N, with its accompanying battens, J J', can be moved along so as to assist in the rinsing operation, and, if preferred, said chamber can be provided with a bed of rollers similar to the ones in G H.

By simply hinging the lid N to the box A, and having only one chamber instead of four, a very effective washing-machine will be produced, of sufficient capacity for all the requirements of a small family.

Another, although a more expensive form of our apparatus, may have a lid and battens for each of the several compartments. In an inferior modification of our invention, the yielding bed may consist of a simple slab of wood or zinc, corrugated or otherwise.

We claim herein as new, and of our invention—

1. A washing-machine, consisting of the yielding bed or frame g I, rollers G, battens J J', stems j j', rock-shaft K k k', and link L, the whole being combined and operating substantially as herein described and set forth.

2. We claim the devices J J', j j', K k k', and L, when attached to the sliding lid N, and adapted to be operated in either of the chambers C, D, or E, as explained.

3. We also claim the devices P Q V v, for enabling the shifting of the lid N, and for securing it at any desired position, for the purpose described.

4. In combination with the sliding lid N, and its described accessories, J J', j j', K k k', and L, we also claim the chambers C, D, E, and F, for the object explained.

5. In a washing-machine constructed substantially as above set forth, we claim the shiftable wringer-rest T U u, as described and set forth.

In testimony of which invention, we hereunto set our hands.

OTIS W. STANFORD,
SELDEN S. SCOVILLE.
